United States Patent Office

Des. 228,640
Patented Oct. 16, 1973

228,640

BUILDING

John C. Long, 90 Broad St., Charleston, S.C. 29401

Filed Mar. 8, 1971, Ser. No. 122,264

Term of patent 14 years

Int. Cl. D25—03

U.S. Cl. D13—1 B

FIG. 1 is a front elevation view of a building incorporating my design, the rear elevation being the same;

FIG. 2 is a side elevation view, both sides being the same; and

FIG. 3 is a top plan view of the building.

I claim:

The ornamental design for a building, substantially as shown and described.
